GRINDING APPARATUS

Clifford L. Garrison, Adrian, Mich., assignor to Oliver Instrument Company, Adrian, Mich., a corporation of Michigan

Application October 24, 1951, Serial No. 252,855

2 Claims. (Cl. 51—100)

This invention relates to a method of grinding and apparatus for carrying out the method, the invention relating more especially to a method of grinding tool bits or similar articles wherein the grinding or abrasive effectiveness is improved over prior methods and apparatus.

It has been conventional practice to configurate and resharpen form tool bits through the utilization of a tool holder provided with a template means for guiding the tool bit during grinding operations and to limit or terminate the grinding operation upon the form or shape of the template being reproduced upon the tool bit. In such devices and methods which have been utilized for this purpose, the peripheral surface of a cylindrical grinding wheel or the flat uniplanar surface of a cup-shaped wheel has been used in conjunction with a uniplanar surface or straightedge cooperating with a template which serves as a guide means to enable an operator to grind the tool bit to the template configuration.

In many form tool bits there are uniplanar zones or wall portions presented to the wheel during grinding operations which are of extensive area. The presentation of a large area of the form tool bit or element to the grinding wheel slows up the grinding operation materially and additionally causes excessive heating of both the grinding wheel and the work. The retardation in the grinding effectiveness appears to be due to the engagement of a large area of surface with the wheel, and in most instances the effectiveness of grinding is reduced as the area of the element presented to the wheel is increased. Furthermore, the less the grinding effectiveness, the more is the heat that is generated through the frictional contact of the work with the wheel, usually accompanied by an increased tendency for the wheel surface to become glazed and to overheat the work. When tool bits formed of very hard alloys such as tungsten carbide are ground by the above-mentioned methods, the tool bits when subjected to any appreciable heating during grinding are readily susceptible of cracking and fracturing. Hence, such prior methods as a practical matter have been unsatisfactory for forming and sharpening hardened form tool bits.

The present invention embraces a grinding apparatus wherein during grinding operations the area of the work presented to the grinding wheel is restricted substantially to a line contact between the work and the wheel.

An object of the invention is the provision of an apparatus for carrying on grinding operations wherein a minimum area of abrasive engagement is established between the work and the grinding wheel whereby the speed of grinding is increased with a minimum of friction and heat developed by reason of the contact between the work and the grinding wheel.

Another object of the invention is the provision of apparatus utilizing a grinding wheel having a transverse, arcuately-shaped, peripheral grinding zone adapted for cooperation with a tool holder and template means whereby articles having uniplanar or convex surfaces may be formed or sharpened by engagement of the work

2

with the transversely curved zone of the wheel in a manner wherein a minimum area of the work is at all times presented to the grinding wheel whereby the speed of grinding is greatly increased over prior grinding methods.

Another object of the invention is the provision of apparatus for presenting work to a grinding wheel in a manner at all times establishing a substantially linear or narrow width of contact or abrasive area between the work and the wheel, the arrangement functioning in conjunction with template means for imparting various configurations or shapes to the work.

A further object of the invention is the provision of an apparatus for presenting a form tool bit or the like to a grinding wheel in a manner whereby grinding operations may be distributed over a substantial area of the grinding wheel to eliminate rapid wear of the wheel in a particular zone, the manner of engagement of the work with the wheel being confined at all times to a narrow linear area.

Another object of the invention resides in the provision of an apparatus for grinding wherein the abrasive zone of the grinding wheel is contoured to an arcuate configuration with which is associated a tool holder, template-follower and guide arrangement to effect a substantially linear engagement of a tool being ground with the grinding wheel.

A further object of the invention resides in an apparatus including a grinding wheel having an arcuately contoured peripheral surface adapted for cooperation with a template and follower means cooperatively associated with a grinding machine and a support for elements to be ground whereby rectilinear surfaces and convex surfaces of the items to be ground may be effectively shaped through engagement with the grinding wheel peripheries without at any time during the grinding operating involving any but a narrow linear engagement with the grinding wheel.

Further objects and advantages are within the scope of this invention such as relate to the arrangement, operation and function of the related elements of the structure, to various details of construction and to combinations of parts, elements per se, and to economies of manufacture and numerous other features as will be apparent from a consideration of the specification and drawing of a form of the invention, which may be preferred, in which:

While I have illustrated a machine especially adapted for carrying out a novel method of grinding or shaping tool bits, it is to be understood that the principles of the invention may be utilized in grinding, shaping or abrading various kinds of tools or other work which may be readily shaped or abraded by grinding methods.

Referring to the drawings in detail, the machine or apparatus is inclusive of a frame structure comprising a base or pedestal 12, an intermediate portion 14 which forms a fluid receptacle or basin to collect the coolant fluid used during grinding operations, the portion 14 supporting an upper frame element 16, the components of the frame being held in assembled relation by bolts (not shown) or other suitable means. The base or pedestal 12 is formed interiorly with a reservoir 13 adapted to contain a supply of coolant fluid which is circulated by means of a suitable fluid circulating pump 15 of conventional character. The pump is connected with a pipe 18 and a flexible hose or tube 19 for conveying the coolant fluid to the grinding surface or zone of the grinding wheel and onto the tool bit or other work being ground, the coolant fluid also serving to entrain and convey cuttings and abraded material away from the grinding zone.

The intermediate portion 14 of the frame is formed to a trough configuration which is bounded at its periphery 21 with an upwardly extending flange to collect the coolant fluid which is returned through a suitable passage to the reservoir in the base 12.

The upper frame element 16 supports a housing portion or enclosure 25 within which is disposed a grinding wheel 27 mounted upon a shaft 28 journaled in suitable bearings (not shown) carried by the frame element 16. A pulley 30 is secured to one end of the shaft and is engaged by a power transmission belt 32 connected with a second pulley 33 driven by a motor 35 supported by the base portion 12. The pulley arrangement and belt 32 are enclosed within a suitable sheet metal shroud 34.

The grinding wheel housing 25 has a downwardly extending portion 36 which is bored to accommodate a shaft 37 whereby the housing 25 and elements carried thereby are pivotally supported for adjustment about the axis of the shaft 37 relative to the grinding wheel for purposes to be hereinafter explained. The housing 25 is made of separable sections so as to admit the assembly of the housing to enclose the grinding wheel 27. Means is provided for adjusting the housing 25 about the axis of its supporting shaft 37. To this end, the housing 25 is provided with a boss 40 which is bored to accommodate a shaft 41 having a threaded portion passing through a nut 43 which is swivelly supported for movement about the axis of a supporting stub shaft 45. The shaft 45 extends through a bore provided in a projection 47 integrally formed with the frame 16. The shaft 41 is provided with a suitable hand wheel 48, rotation of which causes the threaded portion of the shaft 41 cooperating with the nut 43 to move or adjust the housing structure 25 about the axis of the housing supporting shaft 37.

In carrying on grinding or abrading operations, the tool bit or element to be resharpened or shaped to a predetermined configuration is preferably supported upon a relatively movable member or tool holder disposed in predetermined relation to the grinding wheel. The arrangement includes adjusting means to grind tool bits or other work of various sizes and shapes as well as to impart various clearance angularities thereto. The forward portion of the housing structure 25 is provided with a ver-

tically extending portion 50 provided with ways 51 upon which is slidably supported a member 52. The member 50 is provided with a threaded bushing 53 through which a threaded shaft 54 extends, the upper portion of the shaft journaled in a boss portion 56 secured to the member 52, a hand wheel 58 being secured to the extremity of the shaft 54. Rotation of the hand wheel 58 threads the shaft 54 relative to the threaded bushing 53 carried by the portion 50 to cause rectilinear movement of the member 52 along the ways 51. The member 52 is provided with a plurality of graduations 60 arranged for cooperation with a relatively stationary index 61 formed on member 50 to facilitate the accurate rectilinear positioning or adjustment of the member 52. A grinding machine of this character is disclosed and described in U. S. patent to Edd C. Oliver, No. 2,552,645.

The member 52 is provided with means upon which a tool bit holder or supporting member may be mounted during grinding operations. In the apparatus illustrated, 20 the member 52 is formed with a forwardly extending ledge 64 which carries a ball-shaped element or support 66 for a tool holder 68. The holder 68 is of the character illustrated in Figures 2, 3 and 6 and is adapted to carry or support a tool bit 70 or element to be ground, the lower portion of the holder 68 being configured with a semispherical socket 71 adapted to snugly fit the ball support 66 in a manner to be manually movable or oscillatable about the center of the spherical or ball-shaped support 66.

The upper extremity of the holder 68 is provided with a 30 pad portion 74 adapted to support a template 75 which may be securely held in place by means of a thumb screw 76 threaded into a bore in the upper end of the holder. The operative edge portion 78 of the template may be shaped or configured to the contour to be ground or 35 imparted by abrasion to the tool bit and is adapted for cooperation with a guide block or plate 80 having its forward face 81 of convex curvature for a purpose to be hereinafter explained.

The tool bit or blank 70 is supported in the holder 68 in a manner whereby it may be quickly inserted and removed. As illustrated particularly in Figures 3 and 6, the bit 70 is mounted in a grooved block 83 which is engaged by a cam locking member 85 pivoted upon a pin 86, a manipulating screw 87 engaging cam member 85 to force 45 the latter into locking engagement with the block 83 to secure the tool bit in the holder.

One of the important features of the present invention is the provision of a method whereby the entire operative or cutting portion of a tool bit may be rapidly fashioned, 50 ground or abraded to the desired configuration of the pattern or operative contour of the template 75. In the illustrated embodiment of the tool holder, the tool bit retainer block 83 is disposed so that the upper surface of the tool bit 70 is midway between the center of the ball 55 receiving socket 71 and the template 75. By this arrangement the template pattern may be made twice the size of the shape to be imparted to the nose of the tool bit thus providing for a high degree of accuracy of formation of the cutting or operative portion of the tool bit.

60 The invention includes the feature of presenting the tool bit to the grinding wheel in such a manner that during the reproduction of the template configuration on the tool bit by the grinding operation, the zone of engagement of the tool bit with the grinding wheel is a narrow linear area of contact. In this manner, grinding may be carried on at a rapid rate with a minimum of friction developed because of the minimum zone of grinding. As a grinding operation progresses in imparting the desired shape to the tool bit, the grinding area approaches a line contact, 65 a condition attained substantially at the time of completion of the grinding operation as determined by the template. Thus by reducing the zone of actual abrasion to a minimum area, applicant has obtained the benefit of increased abrasive speed and at the same time reduced to 70 a minimum the possibilities of overheating either the

wheel or the tool by a reduction in the friction heat developed by grinding.

In a preferred apparatus, the peripheral zone of the wheel 27 upon which grinding operations are carried on is of a transverse convex curvature as exemplified in Figures 4, and 5 and 12, the arc of curvature of the wheel periphery being indicated at 90. It is imperative that there be an accurate correspondence in curvature of the guide means for the tool bit holder and the transverse curvature of the grinding wheel in order that the shape of the template be accurately reproduced on the tool bit by grinding. To attain this coordination, the abutment or guide 80 for the template 75 has its forward face curved in a transverse direction as at 81 of a radius twice that of the transverse curvature of the peripheral grinding zone of the wheel 27. This relation is diagrammatically illustrated in Figure 12.

The illustration in Figure 5 of the drawings exemplifies the character of engagement of the formed end portion of the tool bit 70 with the curved grinding wheel face whereby a very narrow band or substantially a line engagement is established between the tool element being ground and the grinding wheel. In Figure 5 the engagement of the template 75 with the curved surface 81 of the template guide or abutment 80 is superimposed to illustrate the character of engagement of the template contour with the curved guide. It will be apparent from the foregoing description that the operator manipulates the tool holder 68 in a manner to oscillate the holder about the universal or ball support 66 so that all of the nose portions or cutting zones of the tool bit are brought into grinding or abrading engagement with the grinding wheel face as permitted by the contour of the template 75 engaging the curved guide 80 which serves to limit the extent of grinding of the tool bit at any one setting of the tool bit in the holder. By reason of the transverse convex curvature of the grinding wheel and the mounting of the tool so that all portions of the nose end thereof may be presented to the wheel by manipulation of the holder 68 about the center of the support 66, the grinding area or engagement of the wheel with the tool does not exceed a narrow linear zone of contact which in practical operation provides a minimum area for effecting grinding operations. By providing for a minimum area of grinding, the cutting or abrading speed is greatly increased and the friction which ordinarily would be designated as waste heat energy is reduced to a minimum. Hence, heating of the grinding wheel and the tool is also proportionately reduced and the grinding efficiency thereby improved.

The grinding apparatus of the invention is especially adaptable for grinding extremely hard tools such as those fabricated of tungsten carbide, and they may be ground successfully through the use of this apparatus because of the presentation of a minimum area thereof to the grinding wheel. Applicant's apparatus is usable to advantage in all forms of tool bit contour or configuration except where curved surfaces of the tool bit are of concave character greater than the arc of transverse curvature 90 of the grinding wheel. Flat or uniplanar edge surfaces such as the surface 72 of the tool may be abraded by this method as the relative clearance afforded by the curvature 90 of the grinding wheel results in restricting the zone of abrasion to a narrow linear area.

It is to be understood that the phrases "line contact" and "line engagement" as used herein are relative in character as a grinding engagement necessarily abrades material of the tool bit and, hence, the actual line engagement obtains at the moment the template contour engages the abutment 80 to limit further abrasion or grinding. Thus when it is desired to shape, resharpen or reshape a form tool, the tool bit must necessarily initially project a distance forwardly of the tool holder 68 to insure that the tool engages the grinding wheel before the template 75 engages the block 80. Hence, during the period that material is being removed by grinding in a zone wherein

the template 75 has not yet engaged the abutment 80, the grinding zone of contact with the tool will have an appreciable width, but at no time is such zone more than a few thousandths of an inch which is a relatively small grinding zone and which may be considered a line contact as compared with prior methods of grinding.

After the nose portions of the tool bit have been brought into grinding engagement with the wheel and the grinding in such several zones approaches completion because of the limiting factor of the template 75 engaging the curved surface 81 of guide 80, the finish grinding of all points on the tool in effect presents only a line engagement thereof with the wheel.

To effectively utilize my apparatus for grinding to its fullest efficiency, the apparatus includes a means for presetting the tool bit in the holder 68 to accurately predetermine the extent of material to be removed from the tool bit at one grinding operation. The grinding machine is provided with a ball-shaped support 100. As illustrated in Figure 1, it is equipped with a hardened plate 101 in alignment with the position of the tool 70 when the holder 68 is engaged with the ball support 100. The machine is provided with a micrometer arrangement including an adjustable member 103 whereby the template 75 engages the member 103, the latter being set or adjusted to a position indicating the extent that the tool bit 70, in contact with the indexing plate 101, projects forwardly of the template; and in this manner the amount of material to be removed from the tool bit 70, that is, the extent of the grinding operation at a single setting of the tool, may be determined. An arrangement of this general character is disclosed and described in detail in Oliver Patent No. 2,552,645. However, by reason of the transverse curvature of the grinding wheel periphery, the surface of the micrometer head 103 is a spherical section, the radius of which is the same as that on the guide abutment 80. The transverse curvature of the surface of plate 101 is the same as the transverse curvature of the grinding wheel, i. e., having a radius one-half that of the curved abutment surface of member 80.

The grinding machine illustrated is equipped with a template forming device which includes a ball-shaped tool holder support 105, a gauge or abutment block 107 and a supplemental grinding wheel 109, the latter being preferably of a cup-shaped configuration as illustrated in Figure 1. The grinding wheel 109 may be independently driven by an electric motor 112 which is mounted upon a plate 114 slidably supported upon horizontal ways 115 formed on the grinding machine frame 16. The plate 114 supports a revoluble threaded member 116 cooperating with a relatively stationary nut 118, the threaded member being manipulated by means of a hand wheel 120 to adjust the relative position of the supplemental grinding wheel 109.

In the use of the template forming device, a master form tool is inserted in the tool holder 68 in lieu of a tool bit blank and a template blank is secured to the upper end of the tool holder by means of the clamping screw 76. The socket 71 of the tool holder is then engaged with the ball support 105 and the template blank urged into engagement with the supplemental grinding wheel 109 by manual pressure applied to the tool holder by the operator. The grinding of the template continues until all portions of the cutting contour of the master tool bit engages the abutment or gauge block 107. In this manner the template is accurately ground to a contour double the size of the contour of the master tool bit. The construction and details of template formation by this method are disclosed in Oliver Patent No. 2,552,645.

Figure 12 is a diagrammatic view illustrating the relation of the transversely curved periphery of the wheel 27 and the curved guide surface 81 of the abutment 80. As the holder 68 supports the tool bit or work 70 midway between the center of the ball support 66 and the tem-

plate 75, the radius of curvature of the guide surface 81 is twice that of the transverse curvature of the grinding wheel 27.

The present invention is inclusive of an apparatus for shaping the peripheral grinding zone of the wheel 27 to a transverse arcuate configuration to carry out the grinding. As illustrated in Figure 7, a wheel cutting or truing member 125 which is equipped with a diamond point 126 or the like for engagement with the wheel to be contoured is supported in a bore formed in a holder 127. The wheel cutting or contouring tool 125 is adjustably held in the holder 127 by means of a threaded securing screw 129. The lower extremity of the holder is formed with a socket 131 of semispherical shape adapted to fit over the ball supports 66 and 100. By this mounting means the holder 127 is adapted for oscillatory movement about the center of curvature of the ball-shaped member 66 so that the diamond cutting tool 125 may be brought into engagement with the peripheral area of the grinding wheel 27.

The upper extremity of the holder 127 is formed with a recess 133 within which is mounted a pin 134 adapted for engagement with the curved abutment or guide surface 81 to limit or determine the extent of movement of the truing diamond 126 toward the grinding wheel.

The pin 134 is preferably formed with an arcuate or curved zone 138. The curvature of the zone 138 is the same as that of the abutment block surface 81, and during the formation of transverse curvature on the periphery of the grinding wheel 27 by means of the diamond truing device 126, the engagement of the curved surface 138 of pin 134 with the curved surface 81 of the abutment 80 assures an arcuate guidance of the wheel truing or cutting diamond 126 over the peripheral area of the grinding wheel. Wheel truing diamonds, because of their hardness, are processed under conditions making it sometimes difficult to center the cutting point of the diamond 126 with the longitudinal axis of the pin portion 125. Thus by utilizing a curved surface on the pin 134 any error in the centering of the diamond cutting point with respect to the axis of the pin portion would not affect the accuracy of the curvature formed on the grinding wheel.

In the operation of the apparatus for contouring the periphery of the grinding wheel 27, the holder 127 may be disposed upon the ball support 100 and the pin 134 carried by the holder 127 engaged with the micrometer head 103, which is initially set at index or zero position. The micrometer head 103 may be adjusted forwardly the amount desired and the diamond point 126 of the member 125 then brought into engagement with the locating plate 101 and the screw 129 tightened upon the member 125 to secure the latter in position in the holder 127. When the adjustment of the wheel truing means has been effected in this manner, the socket 131 of the holder 127 is engaged over the ball support 66 and the arcuate surface 138 of pin 134 urged toward the guide or abutment 81, thus bringing the wheel cutting diamond 126 into engagement with the peripheral surface of the grinding wheel 27. The operator oscillates the holder 127 around the center of the ball support 66 as an axis to move the diamond 126 over the area of the peripheral surface of the grinding wheel. The extent of movement of the truing diamond toward the wheel is determined by engagement of the curved surface 138 of pin 134 with the curved guide surface 81. The operator continues to urge the holder toward the guide 81 and oscillates the holder transversely over the arcuate path determined by the guide 81 until the diamond 126 has imparted a curvature to the grinding wheel determined by the pattern of curvature of the guide 81.

The master template formed from a master tool by the supplemental grinding wheel 109 is secured in the tool holder 68 in the manner hereinbefore pointed out. The holder 68 is then engaged with the ball support 100, 75

a form tool blank 70 or a form tool bit to be resharpened is fitted into the retaining block 83 in the manner shown in Figure 3 and the forward edge of the template engaged with the micrometer head 103. The micrometer may be adjusted to a position determining the depth of material desired to be ground from the tool bit or blank 70 which is engaged with the abutment or indexing plate 101, the tool bit or blank being then secured to the holder 68 by manipulation of the locking cam 85 through the medium of the screw 87. The holder 68 carrying the form tool bit or blank and the template is then disposed with the socket 71 of the tool holder engaging the ball support 66. The operator then manually urges the holder toward the grinding wheel with the template aligned for ultimate engagement with the guide or abutment 80, which action brings the cutting end zone of the form tool blank or bit into engagement with the grinding wheel.

Due to the transverse curvature of the periphery of the grinding wheel, only a very narrow, substantially vertical band or zone of the tool bit or blank engages the wheel 27 so that grinding or abrasion takes place at a rapid rate. The operator continues the grinding operation, oscillating the holder 68 about the center of the ball support as an axis until all portions of the pattern of the template 75 have been engaged with the abutment guide surface 81, and at the finish grinding, that is, at the point where the template engages the abutment, the grinding area of the tool engaging the grinding wheel is substantially line contact. Thus, by this grinding apparatus, the removal of material by abrasion is very rapid because of the limited area of abrasion taking place at any particular moment. Thus, hardened tools, such as tungsten carbide, may be successfully abraded and formed to predetermined desired configuration through the use of the apparatus herein shown and described.

It is apparent that, within the scope of the invention, modifications and different arrangements may be made other than is herein disclosed, and the present disclosure is illustrative merely, the invention comprehending all variations thereof.

What I claim is:

1. Apparatus for grinding form tools in combination with a grinding machine having a frame supporting a rotatable grinding wheel formed with a transversely curved grinding zone and a spherically shaped mounting element for a tool carrying holder, means for adjusting the holder mounting element relative to the grinding wheel in a direction substantially tangential of the periphery of the wheel, a form tool-carrying holder having one end supported upon the mounting element for oscillatory movement about the center of said spherically shaped element, the opposite end of the holder carrying a template shaped to the configuration to be imparted to the form tool by engagement with the grinding wheel, said holder being formed with means intermediate its ends for supporting a form tool to be ground, an abutment member having a curved surface of a radius substantially larger than that of the transverse curvature of the peripheral grinding zone of said grinding wheel arranged to be engaged by the template, the curved surface of said abutment member and the curved grinding zone of said grinding wheel at the point of contact with said tool having the planes of their arcs of curvature in spaced parallel relation with one another and their arcs of curvature located on the surface of a cone vertically generated from the center of said spherically-shaped mounting element, whereby grinding of the form tool is effected through a comparatively narrow linear zone tangentially of the periphery of the grinding wheel.

2. Apparatus for grinding form tools as in claim 1, and wherein the radius of the curved surface of said abutment member is substantially twice that of the transverse

curvature of the peripheral grinding zone of said grinding wheel.
